UNITED STATES PATENT OFFICE.

ABEL MARTIN, OF TONOPAH, NEVADA.

LOGGING HOOK.

Application filed March 21, 1922. Serial No. 545,431.

To all whom it may concern:

Be it known that I, ABEL MARTIN, a citizen of the United States, residing at Tonopah, in the county of Nye, State of Nevada, have invented certain new and useful Improvements in Logging Hooks; and I do hereby declare the following to be a full, clear, and exact description of the invention, such as will enable others skilled in the art 10 to which it appertains to make and use the same.

This invention relates to new and useful improvements in hooks and particularly to hooks used in logging camps.

15 One object of the invention is to provide a hook of this character which will not accidentally open to release the ring engaged therewith.

Another object is to provide a hook of this 20 character which is simple in construction, and which can be easily and quickly opened to release the ring when desired.

Other objects and advantages will be apparent from the following description when 25 taken in connection with the accompanying drawing.

In the drawing:

Figure 1 is a side elevation of the hook showing the same in closed position and a 30 ring engaged therewith.

Figure 2 is an inverted perspective view of the hook in open position.

Referring particularly to the accompanying drawing 10 represents a hook having its 35 inner end bifurcated, as shown at 11, for the reception of the latch member 12, the latter being supported in said bifurcation by the pivot pin 13 and being curved at its outer end toward the hook, as shown at 25. The 40 said latch member is provided with a headed stem 14 on which is swiveled the ring loop 15.

The bill of the hook 10 is broadened at 16 to form the two shoulders 17 which shoulders, as well as the extremity of the bill, being 45 beveled, as shown at 18 and 19, respectively. The said bill is also reduced in thickness, vertically, and produces the inner beveled shoulder 20.

50 The outer end of the latch member 12 is formed with a longitudinal channel 21, in its

lower or inner face, and formed transversely of said face, and inwardly of the tip thereof, is a channel 22. The formation of the transverse channel results in the depending ears 55 23 which are arranged to straddle the bill of the hook 10, inwardly of the lateral projections of the broadened portion 16, and against the beveled shoulders 18. The said projections are received in the transverse 60 channel 22, as shown in the drawing, and especially in Figure 1.

The ring or link of a chain 24, is engaged with the hook 10, and then the latch member 12 is swung down to engage the bill of the 65 hook in the manner just described. The combined pull of the ring 24 on the hook and the pull upon the ring 15, fastened to the curved portion will serve to maintain the latch member in proper engaged position 70 with the bill of the hook and will securely hold it against displacement. This holding action is increased through the medium of the curved outer end of the member 12, as will be readily understood. Thus forward 75 pull on the hook causes the latch member to automatically swing into engagement with the bill of the hook and remain in such engaged position.

What is claimed is:

80 A logging hook comprising a hook proper having its bill reduced in thickness and widened to form lateral projections having beveled end faces, and a latch member pivotally supported by the inner end of the 85 hook and having its outer end longitudinally channeled to produce depending wings for straddling engagement with the bill of the hook inwardly at the projections, said latch member being transversely channeled 90 to receive the said lateral projections, the latch member being provided with hook engaging means at its outer end, the hook engaging means and the channeled end of the latch being at opposite sides of the longitudinal axis of the hook.

95 In testimony whereof, I affix my signature in the presence of two witnesses.

ABEL MARTIN.
